UNITED STATES PATENT OFFICE

2,556,350

TIE PLATE FOR RAILROAD TRACKS

Louis Tucker and Hathaway Hill, Stanford, Ky.

Application June 17, 1949, Serial No. 99,694

1 Claim. (Cl. 238—288)

1

The present invention relates to tie plates for railroad tracks and it consists in the combinations, constructions and arrangements of parts herein described and claimed.

Generally the invention comprises a tie plate for railroad tracks consisting of a single piece of flat metal having a pair of rail-supporting portions for each of an opposite pair of conventional rails. Each pair of such rail-supporting members is interconnected by a longitudinally extending web and one of each pair of members is joined to its counterpart beneath the opposite rail by a transversely extending web.

It is an object of the invention to provide a tie plate for railroad tracks which will provide a simple connecting means between a rail and a tie.

Another object of the invention is the provision of a device of the character set forth which is simple and inexpensive in construction and yet effective and efficient in use.

Another object of the invention is the provision of a device of the character set forth having means for maintaining the ties of a railroad in proper alignment with one another.

A further object of the invention is the provision of a device of the character set forth wherein simple and effective means is provided for maintaining the rails of a railroad in proper alignment with each other.

Other and further objects of the invention will become apparent from a reading of the following specification taken in conjunction with the drawing, in which:

Figure 1 is a plan view of an embodiment of the invention shown in use with a conventional railroad track,

Figure 2 is a reduced plan view of the device forming the present invention removed from the railroad track, and

Figure 3 is a sectional view taken along line 3—3 of Figure 1.

Referring more particularly to the drawing, there is shown therein a conventional railroad track having ties 10, 11, 12, 13 et cetera and rails 14 and 15.

The device forming the present invention consists of a single flat piece of metal and comprises a pair of rail-supporting members 16 and 17 adapted to lie adjacent one end of adjacent ties as, for example, ties 11 and 12 and interconnected by a web 18 extending in a direction parallel to the rails.

A like pair of rail supporting members 19 and 20 are adapted to lie upon the same ties 11 and 12 adjacent the opposite ends thereof and are interconnected by a web 21 which also extends in a direction parallel to the rails.

A transversely extending web 22 interconnects the members 17 and 20 and is adapted to lie upon but one tie, in this case the tie 12.

2

The web 22 is provided with a centrally disposed opening 23 for the reception of a spike 24 whereby to attach the same to the tie 12 and the members 16, 17, 19 and 20, which are substantially square in contour, are each provided with a pair of diagonally disposed openings 25 and 26 for the reception therethrough of spikes 27 and 28, respectively.

In operation, it will be apparent that the device forming the present invention may be placed upon a pair of adjoining ties such as 11 and 12 and that thereafter the rails 14 and 15 may be laid thereover. The web 22 is fastened to the tie 12 by means of the spike 24 and the spikes 27 and 28 are then driven through the openings 25 and 26 into the ties 11 and 12 therebelow, the heads of such spikes engaging opposite sides of the rail to hold the same firmly in position. It will be apparent that the webs 18 and 21 will prevent the ties 11 and 12 from moving closer to or away from each other and that the web 22 will act to hold the rails 14 and 15 in proper spaced relation. The device may be utilized to the greatest advantage on curvular sections of the railroad track but is, of course, useful upon straight stretches thereof, also.

While but one form of the invention has been shown and described herein, it will be readily apparent to those skilled in the art that many minor modifications may be made without departing from the spirit of the invention or the scope of the appended claim.

What is claimed is:

A tie plate for railroad tracks comprising a single piece of flat metal having a transversely extending web, a rail-supporting member at each end of said web, a longitudinally extending web at the same corresponding side of each of the rail-supporting members, and a second rail-supporting member at the free end of each of the longitudinally extending webs, said longitudinally extending webs being parallel to each other and each adapted to lie beneath one rail of a railroad track, and said transverse web adapted to lie upon a tie of a conventional railroad track.

LOUIS TUCKER.
HATHAWAY HILL.
